UNITED STATES PATENT OFFICE.

JOHN CARLSON FIELD, OF BUTTE, MONTANA.

FLY SWATTER.

1,420,536.

Specification of Letters Patent. Patented June 20, 1922.

Application filed April 2, 1921. Serial No. 457,887.

To all whom it may concern:

Be it known that I, JOHN C. FIELD, a citizen of the United States, and a resident of Butte, in the county of Silver Bow and State 5 of Montana, have invented certain new and useful Improvements in Fly Swatters, of which the following is a specification.

This invention relates to fly swatters especially adapted for use on screen doors.

10 An important object of this invention is to provide a fly swatter which is automatically actuated by the movement of the door to which it is attached and which is automatically set by the movement of the door.

15 A further object of the invention is to provide a fly swatter of the character described having a detachable receiver for collecting the flies as they are killed so as to prevent the same from falling to the floor 20 and marring the appearance of the entrance.

25 The invention forming the subject matter of this application aims also to provide a fly swatter which may be conveniently applied to a screen door or the like at any time and which does not mar the appearance of the door.

30 A further object of the invention is to provide a fly swatter of the class described which is efficient, reliable in use and cheap to manufacture.

Other objects and advantages of the invention will be apparent during the course 35 of the following description.

In the accompanying drawings forming a part of this application and in which like numerals are employed to designate parts throughout the same,

40 Figure 1 is an elevation of the improved fly swatter applied to a door, the door being shown closed.

Figure 2 is a plan view of the improved fly swatter applied.

45 Figure 3 is a fragmentary side elevation of the improved fly swatter applied, the same being shown set or prior to releasing the swatter.

50 Figure 4 is also a fragmentary side elevation of the improved fly swatter, the parts being shown in the positions they occupy subsequent to releasing the swatter.

55 Figure 5 is a fragmentary plan view of the improved swatter applied, the parts thereof being shown in their inoperative positions.

Figure 6 is a perspective of a latch em-

bodied in the invention, which latch is adapted for holding the swatter in its set position.

Figure 7 is a fragmentary plan view of the improved fly swatter applied to a door, 60 the guide or cam member being shown in section and the door being shown partly open.

Figure 8 is a vertical transverse sectional view through the swatter applied. 65

Figure 9 is a detail sectional view through the swatter, the view illustrating the supporting means for the latch.

Figure 10 is a detail transverse sectional view through a releasing and setting device 70 embodied in the invention.

Figure 11 is a perspective view of the releasing and setting device.

In the drawings the numeral 10 designates a door frame within which a screen door 75 generally designated by the numeral 11 is arranged. The screen door 11 is supported for swinging movement within the doorway by means of spring hinges 12 which serve the usual purpose of urging the door to its 80 closed position.

The improved fly swatter comprises a trap or casing 14 which is of a length sufficient to extend across the reticulated body 14' and which is secured to the door by means of 85 a pair of attaching brackets 16 engaged with the closed ends 17 of the trap.

As illustrated in Figure 8 the trap 14 which is of elongated formation includes a top wall 18 and a rear wall 19 arranged 90 in proximity to the reticulated body 14' and having its lower longitudinal edge portion crimped inwardly to cooperate with the adjacent edge of a fly receiver 20 in forming an entrance for the flies into the trap. 95

Further, the crimped lower longitudinal edge portion of the back 19 forms an inclined guide or baffle 21 which serves to direct the flies into the receiver 20 after being batted against the back 19 by a swatter 100 22. The inclined portion or baffle 21 prevents the dead flies from falling through the entrance opening to the trap. It is understood, however, of course, that the flies crawl up the outer side of the screen 14' 105 and will enter the trap through the entrance opening formed by the lower longitudinal edge portion 23 of the back 19 and the adjacent longitudinal edge of the receiver 20. The receiver 20 includes a reticulated body which 110

is arranged in spaced relation to the screening 14' and has its ends provided with hooks or clamping devices 24 by means of which the receiver is secured to the ends of the trap 14. A spring catch 25 is pivoted to one end 17 and is engaged with the adjacent fastening device 24 for holding the same in engagement with the trap. When desired the receiver may be readily detached 10 for the purpose of removing the flies dropped from the trap after being killed. By reason of this construction, an accumulation of dead flies about the doorway is prevented.

15 It is believed to be apparent that the flies will crawl up the screening 14' and enter the trap 14 by way of the opening in the bottom of the same and are subsequently struck by the swatter 22 upon being released.

20 The swatter 22 comprises a reticulated body having upper and lower walls in the form of angle irons having outwardly directed flanges 26. The outwardly directed flanges 26 of the upper and lower sides of the swatter are formed with longitudinal slots 27 which freely receive the vertical portions of U-shaped cranks designated by the numeral 28. With reference to Figure 1 it will be observed that the U-shaped cranks 28 are preferably three in number and are provided with L-shaped arms 30 to which a longitudinally movable operating rod 31 is pivotally connected. It might be stated 25 that when the rod 31 is moved to the limit of its movement to the left the swatter will be held in a set position as illustrated in Figure 8. When the swatter 22 occupies the set position illustrated in Figure 8 it 30 is because the rod 31 is held in the position illustrated in Figure 1 by means of a latch 32. The latch 32 is pivotally supported at its rear end between a pair of upstanding ears 33 which are extensions of a base 34 secured to the top 18 by means of fastening devices 35. When the rod 31 is moved to the left by a means to be later described the laterally enlarged terminal portion 37 of the latch is engaged with a 35 locking notch 38 formed on the intermediate portion of the rod.

40 As illustrated in Figure 7 the intermediate portion of the rod 31 is provided at a point spaced from the notch 38 with an enlarged portion 40 having a laterally projecting apertured ear 41 to which one end of a contractile coil spring 42 is connected. The other end of the contractile coil spring is anchored to the door as indicated at 44 so 45 as to urge the rod to move longitudinally to the right and thereby swing the swatter 22 inwardly into contact with the back 19 for killing the flies which may have entered the trap. Of course when the rod 31 is 50 moved to the left the latch 32 is engaged

55 with the notch 38 so that even though the spring is expanded it is temporarily held inoperative. With the parts thus positioned the swatter is held in a set position and when the latch 32 is elevated the spring 42 60 will be free to instantly swing the rod 31 to the right for engaging the swatter with the back 19.

65 The means employed for setting the rod 31 and consequently the swatter includes a 70 trigger generally designated by the numeral 46 and which as illustrated in Figure 11 comprises an intermediate plate 47 and terminal arms 48 and 49. The intermediate plate 47 is provided with a vertically ar- 75 ranged slot 50 which freely receives that portion of the rod 31 between the enlargement 40 and the notch 38. To set the device the trigger 46 is moved to the left and the intermediate plate 47 is engaged with an 80 annular shoulder 51 formed at one end of the enlargement 40 and the movement of the trigger 46 is continued to the left until the notch 38 is engaged by the latch 32 whereby the rod 31 is held in the set position. 85

90 The terminal portion of the arm 48 is provided with a laterally projecting cam 51' having oppositely arranged upper and lower inclined faces 53 which are adapted to contact with the upper and lower faces of the 95 inclined cam or terminal portion 37 of the latch 32. Assuming that the device is set and that the trigger 46 is moved to the left the upper inclined face 53 of the cam 51' will contact with the under side of the cam 100 37 and thereby elevate the latch for releasing the rod 31 and consequently the swatter. The latch 32 is pressed downwardly into contact with the rod 31 by means of a spring 105 55.

110 The continued movement of the trigger 46 after releasing the swatter engages the intermediate plate 47 with the annular shoulder 51 so that the rod 31 is again moved to the left to its set position.

115 The means for operating the trigger consist of a crank 56 having a laterally projecting arm 58 pivotally connected to the curved terminal portion of the arm 49. The crank 56 is also provided with an upper laterally projecting arm 60 having a roller 61 mounted for movement within a guide 62. The guide 62 which is permanently secured to the door frame is provided with branches 64 and 65 arranged substantially at right angles to 120 each other and adapted for controlling the movement of the crank which is generally designated by the numeral 60. When the door is closed the roller moves into the rear or closed end portion of the branch 65 and 125 when the door is moved to its open position the roller 61 is moved through the branch 65. The terminal of the branch 65 is enlarged so that when the door is closed the roller 61 130 will be directed into the guide. However,

the crank 60 is held in a set position by means of frictional contact with a bearing plate 68 which rotatably supports the same.

In operation the opening of the door will 5 cause the crank 60 to draw the rod 31 to the left and thereby set the device. When the door is again opened the first movement of 10 the same will cause the crank 60 to rotate slightly so that the cam 51' is moved beneath the latch 32 for elevating the same whereupon the swatter is released for killing the flies which may have entered the trap.

Having thus described the invention, what I claim is:—

15 1. An apparatus of the class described comprising a casing having its bottom open, a swatter arranged within the casing, and a receiver arranged beneath the casing.

20 2. An apparatus of the class described comprising a casing having its bottom open, a swatter arranged within the casing, a receiver arranged beneath the casing, and operating means for said swatter.

25 3. An apparatus of the class described comprising a reticulated casing having a rear wall provided with a baffle, a swatter arranged within said body, and a receiver arranged beneath said body and having one longitudinal edge portion arranged in spaced 30 relation to the baffle thereby defining an opening.

35 4. A fly trap comprising an elongated casing having its bottom open, said casing being provided with a reticulated back and having its lower longitudinal edge portion crimped to define a baffle and an inclined wall, a swatter adapted to engage said back, and a receiver arranged beneath said casing and having one longitudinal edge portion arranged 40 in spaced relation to the crimped portion of said back to define an entrance opening, said baffle being adapted to direct the batted flies into the receiver.

45 5. The combination with a door having a reticulated body, of a casing traversing the upper portion of the reticulated body and having a reticulated back, the lower longitudinal edge portion of said back being provided with a rib defining an inclined baffle 50 and one wall of an opening, a swatter to engage said back, and a receiver secured to said casing and having one longitudinal edge portion arranged in spaced relation to said wall thereby forming an opening adjacent the upper portion of said reticulated body, said receiver being arranged in spaced relation to said reticulated body.

60 6. The combination with a door having a reticulated body, of a casing traversing the upper portion of the reticulated body and having a reticulated back, the lower longitudinal edge portion of said back being provided with a rib defining an inclined baffle and one wall of an opening, a swatter to engage said back, a receiver secured to said

casing and having one longitudinal edge portion arranged in spaced relation to said wall thereby forming an opening adjacent the upper portion of said reticulated body, said receiver being arranged in spaced relation to 70 said reticulated body, and operating means for said swatter.

7. The combination with a casing having means whereby the same may be attached to a door, of a swatter arranged within the casing, and means actuated by the movement of the door for operating said swatter.

75 8. The combination with a casing having means whereby the same may be attached to a door, of a swatter, a longitudinally movable rod connected to said swatter, means detachably holding said rod in such position whereby said swatter is held in a certain position, and means associated with said rod for swinging said swatter to its operative 80 position.

9. The combination with a casing having a swatter, of cranks connected to the swatter, a longitudinally movable rod connected to said cranks, means to secure said rod and 90 said swatter in a set position, and a spring connected to said rod for moving the same longitudinally when released whereby said swatter is swung into contact with one wall of said casing.

95 10. The combination with a casing adapted for attachment to a door and having a swatter, of a rod connected to said swatter arranged therein and having a notch, a latch carried by said casing and engaging said 100 notch, a trigger cooperating with said latch to release the same, a spring for swinging the swatter to its operative position, and means operated by the movement of the door to operate said trigger.

105 11. The combination with a casing having means whereby the same may be attached to a door, of a swatter, of a rod connected to said swatter and having a notch, a latch carried by said casing and engaging said 110 notch, a trigger cooperating with said latch to release the same, a spring connected to said rod for swinging the swatter to its operative position, and operating means for said trigger.

115 12. The combination with a casing having means whereby the same may be attached to a door, of a swatter, a longitudinally movable rod connected to said swatter, a latch adapted to engage said rod to secure 120 the same and said swatter in a set position, said rod being provided with an abutment, a trigger slidable with relation to said rod and adapted to engage said abutment and having means to release said latch, and operating means for said trigger.

13. The combination with a casing having means whereby the same may be attached to a door, of a swatter, a longitudinally movable rod connected to said swatter, a latch 130

adapted to engage said rod to secure the same and said swatter in a set position, said rod being provided with an abutment, a trigger slidable with relation to said rod and adapted to engage said abutment and having means to release said latch, operating means for said trigger, and a spring connected to said rod for moving the same longitudinally when released.

- 10 14. The combination with a casing having a swatter, a rod connected to said swatter, a latch carried by said casing and adapted to engage said rod to secure the rod in a set position, said rod being provided intermediate its ends with an enlargement constituting a shoulder, a trigger having an offset portion adapted to engage said shoulder and having a cam adapted to release said latch, a spring connected to said enlargement for moving the rod when released, and a crank having connection with said trigger for moving the same longitudinally.
- 15 15. The combination with a swatter, of an operating member therefor, means to secure said operating member in a set position, a releasing device for said means, and a crank having a laterally projecting arm secured

to said releasing device, and a guide for controlling said crank.

16. The combination with a guide having branches, a crank having an arm provided with a roller arranged within said guide, said crank being provided with a second arm, a swatter having an operating member, and a releasing device for said operating member connected to the second named arm of said crank.

17. The combination with a casing having means whereby the same may be attached to a door, of a swatter associated with the casing, and automatic means operated by the door to operate said swatter.

18. The combination with a swatter having means whereby the same may be attached to a door, of means actuated by the movement of the door for operating the swatter, and a receiver for the flies.

19. The combination of a spring actuated swatter having attaching means whereby the same may be secured to a door, a restraining device for said swatter and means operated by the movement of the door for releasing said restraining device.

JOHN CARLSON FIELD.
